CLAIM

The ornamental design for a hollow coving for concealing electrical wires, as shown and described.

DESCRIPTION

FIG. 1 is a top plan view of a hollow coving for concealing electrical wires showing my new design;

FIG. 2 is an end elevational view, the opposite end being identical thereto;

FIG. 3 is an enlarged top plan view thereof, the hollow coving being broken in the center to show indeterminate length;

FIG. 4 is an enlarged right side elevational view thereof;

FIG. 5 is an enlarged bottom plan view thereof; and,

FIG. 6 is an enlarged left side elevational view thereof.
